[57] CLAIM

The ornamental design for an athletic team flag, as shown and described.

DESCRIPTION

FIG. 1 is a top plan view of an athletic team flag showing my new design.

FIG. 2 is a side elevational view thereof, the other side, appearing the same.

FIG. 3 is an end elevational view thereof, the other end appearing the same.

The bottom is plain and unornamented.

FIG. 3**FIG. 2****FIG. 1**
